UNITED STATES PATENT OFFICE

135,874

DESIGN FOR A CORN HARVESTER

Charles E. Everett, Racine, Wis., assignor to The
Massey-Harris Company, Racine, Wis., a com-
pany of Maryland

Application June 22, 1942, Serial No. 107,298

Term of patent 14 years

To all whom it may concern:

Be it known that I, Charles E. Everett, a citizen of the United States, residing at Racine, in the county of Racine and State of Wisconsin, have invented a new, original, and ornamental Design for a Corn Harvester, of which the following is a specification, reference being had to the accompanying drawings, forming a part thereof.

Fig. 1 is a side view of a corn harvester, embodying my new design;

Fig. 2 is a view showing the opposite side;

Fig. 3 is a front view; and

Fig. 4 is a rear view thereof.

The characteristic features of my design are shown in full lines.

I claim:

The ornamental design for a corn harvester, as shown and described.

CHARLES E. EVERETT.
